UNITED STATES PATENT OFFICE.

WILLIAM AUSTIN, OF PHILADELPHIA, PENNSYLVANIA.

SHEET-METAL PIPE.

SPECIFICATION forming part of Letters Patent No. 253,493, dated February 14, 1882.

Application filed July 22, 1881. (No model.)

To all whom it may concern:

Be it known that I, WILLIAM AUSTIN, of Philadelphia, in the county of Philadelphia and State of Pennsylvania, have invented certain 5 Improvements in Water-Pipes and Machines for Constructing the Same, of which the following is a specification.

The object of this invention is to produce a sheet-metal spouting or water-conducting pipe 10 which shall be exceedingly cheap in construction, and which shall at the same time possess a sufficient degree of rigidity and stiffness to prevent it from being indented or bent out of shape by the strains and pressures to which it 15 is subjected while being handled and when in use.

To this end it consists in a pipe made in a cylindrical form by seaming the two edges of the metal sheet together longitudinally, as 20 usual, and providing the pipe thus constructed with a spiral rib to give the required stiffness thereto.

I am aware that metallic pipes have been constructed by winding strips of metal in a 25 spiral form and riveting or sealing the edges together, thus producing a spiral seam.

I am also aware that the ends of sheet-metal stove-pipe have been provided with a continuous series of short spiral corrugations or crimps 30 for the purpose simply of contracting the end of the pipe; and this I do not claim, my pipe differing from all others in that its body, having a longitudinal seam, is of substantially a smooth cylindrical form, with the spiral rib 35 formed by creasing the metal to give the required rigidity.

It is preferred, as shown in the accompanying drawings, to make use of a single continuous spiral rib; but it is manifest that the duplication of the ribs would not be a departure 40 from the scope of my invention. It is also preferred, as shown in the drawings, to form the rib by pressing the metal outward; but the same result may be secured by pressing the rib inward instead of outward.

Referring to the accompanying drawings, Figure 1 represents a side elevation of my improved pipe; Fig. 2, a cross-section of the same; Fig. 3, a view of the blank or sheet after being 50 acted upon by the machine, but previous to the closing of the seam or joint; Figs. 4, 5,

and 6, respectively a side elevation, an end elevation, and a top plan view of the machine by which the blank is produced; Fig. 7, a cross-section of the rolls.

Referring to Figs. 1, 2, and 3, A represents the pipe, which may be of tin or other suitable sheet metal, in section of any required length, each section being preferably composed of a single sheet of metal. As represented in the drawings, each section consists of a sheet folded edgewise into a tubular form and having the two edges united in a longitudinal seam or joint, a. The body of the pipe, which is usually of a smooth cylindrical form, is provided, as shown, with a spiral rib, b, this rib being formed by pressing the metal upward from the inside in such manner as to form, when the pipe is completed, a continuous spiral rib encircling the same at a greater or less degree of obliquity, as may be desired.

The manner of constructing or forming the longitudinal joint or seam forms no part of my invention, the ordinary lap-joint or either of the other joints known in the art being adapted 75 for the purpose.

As a means of connecting the sections of the pipe with each other, I provide the ends of the sections with spiral screw-threads or ribs c, which, however, are not claimed as my invention.

By pressing and grooving the metal, as indicated in the drawings, the pipe will be expanded at one end and contracted at the other to a limited extent, permitting the threaded 85 portions to be united the more readily.

Referring to the machine for forming the pipe, which is, so far as I have been able to ascertain, the only practical means for the purpose, it will be seen to consist essentially of two parallel 90 rolls, B C, having their ends provided with journals mounted in boxes in upright frames D, the two rolls being geared together at one end by pinions e. At the opposite end one of the rolls is provided with a gear-wheel, f, 95 driven by means of a pinion, g, to which an operating hand-crank, h, is attached, as shown, so that by turning the crank a positive and equal motion is imparted to the two rolls, their surfaces being turned toward each other in order to pass the sheets of metal between them. The roll C is provided, as shown, with a raised

spiral rib, *i*, encircling the same from end to end, while the roll *B* is provided with a corresponding groove, *j*, into which the rib *i* extends, as shown in the drawings, the arrangement being such that as the rolls revolve the rib of one follows constantly in the groove of the other, the effect of which is to produce in a sheet of metal which may be passed between them a series of curved or oblique ribs in such 10 position that when the sheet is coiled into the tubular form and united at the end they will produce a continuous spiral rib.

In order that the rolls may bend the blank into the tubular form at the same time that 15 the spiral ribs are formed therein, the lower roll is provided, as shown in Fig. 7, with a longitudinal groove, *k*, into which the edge of each sheet is inserted before commencing operation. The edge of the sheet being inserted into the 20 groove, the rotation of the rolls first bends the edge downward at an angle to the sheet, after which the sheet, having its edge retained in the groove, is wound or coiled closely around the lower roll, from which it is removed by springing 25 its edges apart. Upon being removed the sheet presents the appearance represented in Fig. 3. Inasmuch as it is desirable that the two edges of the sheet shall be flat and straight to facilitate the seaming of them together, I 30 prefer to flatten down the ribs on the roll adjacent to the groove *k*, and to make the grooves in such form as to conform closely to these flattened faces. Under this construction of the rolls the oblique ribs are caused to vanish or 35 merge gradually into the sheet of the blank near each edge of the latter, leaving the edges of the blank flat and plain, so that they may be united without difficulty.

For the purpose of forming the threads upon the ends of the pipe, the rolls are provided, as 40 shown in the drawings, with suitable male and female threads, *m* and *n*, formed upon the ends. The contraction and expansion of the respective ends of the pipe are secured by making the ends of the respective rolls of different diameters, as shown in the drawings. 45

The machine above described constitutes no part of the present invention, and will be made the subject-matter of a separate application. It is described herein for the purpose of enabling those skilled in the art to carry my invention into practice. 50

Having thus described my invention, what I claim is—

1. As a new article of manufacture, a sheet-metal pipe having its body-sections stiffened by means of a spiral rib formed by pressing up the metal, substantially as shown and described. 55

2. The improved pipe-section, consisting of a single sheet of metal folded into tubular form, with its edges united longitudinally and having a spiral rib formed thereon, as described and shown. 60

3. A blank for a sheet-metal pipe, consisting of the curved sheet of metal having the oblique ribs *b* raised thereon. 65

4. The improved pipe-blank, consisting of a curved sheet of metal having one flat and one folded edge, and having also the oblique ribs *b* formed thereon, as described and shown. 70

WILLIAM AUSTIN.
